UNITED STATES PATENT OFFICE.

EDGAR H. MONROE, OF WASHINGTON, DISTRICT OF COLUMBIA.

PARKING LAMP FOR VEHICLES.

Application filed June 3, 1920. Serial No. 386,163.

To all whom it may concern:

Be it known that I, EDGAR H. MONROE, a citizen of the United States, residing at 901 Virginia Avenue SW., Washington, District of Columbia, have invented a new and useful Improvement in Parking Lamps for Vehicles, of which the following is a specification.

The object of the invention is to provide an efficient means for furnishing a parking light adaptable to vehicles of all types but more especially designed for automobiles, to dispense with the necessity of leaving either the head or tail lights, or both, in operation, and furthermore to provide a device for the purpose which, regardless of the position of the machine with relation to the road, that is, whether parked parallel or at an angle thereto, will display light in both forward and rearward directions along the road or vehicle path so as to be visible on either line of approach, and also, and particularly, to provide a means whereby the maximum volume of light, or light value, will be concentrated in the directions best suited to the purpose of disclosing the location of the vehicle carrying the lamp, to the end that the minimum candle power may be utilized as a measure of economy in maintenance.

With these general objects in view the invention consists in a construction and arrangement of reflecting media and display zones of which a typical and at the present time a preferred embodiment is illustrated in the accompanying drawing, it being understood however that modifications thereof are contemplated and obviously may be resorted to within the scope of the appended definition without departure from the principle involved.

Referring to the drawings:

Figure 1 is a view of the lamp showing its application to a vehicle.

Fig. 2 is a face view of the lamp proper.

Fig. 3 is an edge view of the same.

Fig. 4 is a sectional view taken in the plane of the axis of the lamp and including the housing.

Fig. 5 is an edge view of the encased lamp to show the mounting thereof upon a wheel guard.

In the illustrated embodiment the lamp consists essentially of opposed or counter reflecting media such as mirrors, 10 and

11, preferably designed on parabolic curves, with a centrally interposed source of light shown as an incandescent lamp globe 12, which may be of relatively low candle power to minimize the consumption of current. 60 The reflectors are provided respectively with light penetrable areas or zones 10^a and 11^a, of any preferred conformation, as sector shaped, with those of one medium disposed opposite or in the path of rays of light reflected from the other medium, and the aggregate of the areas of the light penetrable zones of each medium substantially equal to or approximating the area of the reflecting surface of the other medium. 70 These light penetrable zones may consist of unobstructed openings in the mirrors, formed by cutting away or stamping out the material, and the annular series of openings may be supplemented by central light 75 penetrable zones 10^b and 11^b, with the edges of the disks forming the media flanged as at 13 and suitably secured in a dust and moisture excluding casing or housing 14 having transparent walls 15 for freely exposing the opposite light diffusing faces of the lamp.

The lamp bulb may be detachably seated in a socket 16 carried by a radially disposed post 17 serving as a support for the reflectors and the housing for attachment to a wheel guard or other convenient portion of a vehicle, and preferably the post is jointed as at 18 to provide for revoluble adjustment of the lamp to insure opposite 85 projection of the light in the desired direction regardless of the position of the parked car to which the device is attached.

The advantage of the lamp resides in the concentration of the available light value 90 in the directions of approach to the car from the front and the rear, and in producing with a moderate power or expenditure of fuel an illumination which is discernible and will attract attention at safe distances 100 to properly warn the drivers of approaching vehicles and thus minimize the risk of collision.

I claim:

1. A parking lamp for vehicles having 105 opposed reversely concaved reflecting media and an interposed lighting unit, each medium being subdivided on diametral lines to provide alternately disposed sector shaped light penetrable and reflecting zones 110

arranged respectively opposite alternately disposed sector shaped light reflecting and light penetrable zones of the other medium.

2. A parking lamp for vehicles having
5 stationary opposed reversely concaved para-
bolic reflecting media for reflecting beams
on parallel lines, and an interposed axially
disposed lighting unit, each medium being
subdivided on diametral lines to provide al-

10 subdivided on diametral lines to provide alternately disposed sector shaped light penetrable and reflecting zones arranged respectively opposite alternately disposed sector shaped light reflecting and light penetrable zones of the other medium.

15 3. A parking lamp for vehicles having stationary opposed reversely concaved reflecting media and an interposed lighting unit, each medium being subdivided on diametral lines to provide alternately dis-

20 disposed sector shaped light penetrable and reflecting zones of equal areas, arranged respectively opposite alternately disposed sector shaped light reflecting and light penetrable zones of the other medium.

25 4. A parking lamp for vehicles having op-

posed reversely concaved parabolic reflecting media and an interposed axially arranged lighting unit, each medium being subdivided on diametral lines to provide alternately disposed sector shaped light penetrable and reflecting zones of equal areas, arranged respectively opposite alternately disposed sector shaped light reflecting and light penetrable zones of the other medium.

5. A parking lamp for vehicles having stationary opposed reversely concaved parabolic reflecting media for projecting light beams in parallel lines, and an interposed axially arranged lighting unit, each medium being subdivided on diametral lines to provide alternately disposed sector shaped light penetrable and reflecting zones of equal areas, arranged respectively opposite alternately disposed sector shaped light reflecting and light penetrable zones of the other medium, the peripheries of the opposed media being in a common plane with the lighting unit and perpendicular to the paths of the beams.

EDGAR H. MONROE.
